US00D932828S

(12) **United States Design Patent** (10) Patent No.: **US D932,828 S**
(45) Date of Patent: **** Oct. 12, 2021**

(54) **KNOB FOR OVEN RANGE**

(71) Applicant: **LG ELECTRONICS INC.**, Seoul (KR)

(72) Inventors: **Inhwan Ryu**, Seoul (KR); **Sooyeon Kim**, Seoul (KR); **Hongsik Kwon**, Seoul (KR); **Suhyeon Son**, Seoul (KR)

(73) Assignee: **LG ELECTRONICS INC.**, Seoul (KR)

(**) Term: **15 Years**

(21) Appl. No.: **29/727,376**

(22) Filed: **Mar. 10, 2020**

(30) **Foreign Application Priority Data**

(57) **CLAIM**

The ornamental design for a knob for oven range, as shown and described.

DESCRIPTION

FIG. 1 is a front, right side, perspective view of a knob for oven range showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view within an environment of use.

The broken lines indicate portions of the article that form no part of the claimed design. The broken lines in FIG. 8 illustrate environment that forms no part of the claimed design.

1 Claim, 4 Drawing Sheets
